UNITED STATES PATENT OFFICE

ADAM RAMBACHER, OF MUNICH, GERMANY.

MEANS FOR PREVENTING THE CREEPING OF RAILWAY AND LIKE RAILS.

1,121,866.

Specification of Letters Patent.

Patented Dec. 22, 1914.

Application filed June 19, 1914. Serial No. 846,001.

To all whom it may concern:

Be it known that I, ADAM RAMBACHER, citizen of Germany, residing at Munich, Bavaria, Germany, have invented certain new and useful Improvements in Means for Preventing the Creeping of Railway and like Rails; and I do hereby declare the following to be a full, clear, and exact description of the invention, such as will enable others skilled in the art to which it appertains to make and use the same.

The invention relates to means for preventing the creeping of railway and like rails carried in any manner on sleepers.

The improved clamping device differs essentially from known devices for this purpose by the fact that it has a comparatively very long neck, which embraces the foot of the rail, and by it having a longitudinal web extending from the rear end of the device to the bearing plate of the front of the same, so that the device is strongest at that part which is subjected to the greatest stresses. However, the hook of the clamping bolt adapted to engage the foot of rail can be so constructed that it only projects slightly beyond the rail foot and only embraces the latter to such an extent that the clamping device can also be used without alteration for rails carried by chairs and does not hinder the insertion and withdrawal of the key for wedging the rail in the chair.

The invention is illustrated in the accompanying drawing, in which—

Figure 1 is a front view, and Fig. 2 a side view of the device applied to a rail carried by the sleepers direct. Figs. 3 and 4 are a front and side view respectively of the device applied to a rail supported on the sleepers by chairs.

In Figs. 1 and 2, *a* designates an ordinary railway rail having a broad foot *b*.

In order to prevent creeping of the rail a clamping jaw is detachably secured to the rail. This clamp, made of suitable material, such as a pressed plate of suitable thickness, comprises a long neck *g* embracing one side of the rail foot *b* at the top and bottom and forming a broad channel which closely fits this side of the rail foot. The front part of the narrow neck *g* is bent round to form a face *h*, which is vertical to the rail and forms a supporting or bearing face which is proportionally wide with respect to the rail foot *b*. The neck *g*,

which is preferably curved downward at the front, or may be square instead, may project more or less at *i* beyond the bearing plate *h*. In the constructional example shown the front edge *i* of the neck does not project beyond the bearing face *h*, but is flush therewith, or it may even be slightly set back, so that the plate *h* extending downward for an adequate distance always engages first when pushed toward the wooden or iron sleeper *d*, and bears with a sufficiently large surface against the sleeper.

The bearing plate *h* is preferably provided underneath the neck *g* with a recess *k*, which stiffens the device. This recess *k* may, however, be omitted, for instance in the case of a clamping device the neck *g* of which projects beyond the face *h*. The neck *g* forms at the bottom a web plate *o*, which is parallel with the rail, and a prolongation of which forms the bearing plate *h*, at right angles to the plate *o*, so that the latter forms a stiffening rib. The stiffening plate *o* renders the clamping device extremely strong at the most stressed part so that the device is capable of taking the greatest strains and is consequently absolutely reliable. As already mentioned, the whole clamping device is made in one piece.

In proximity to the recess *k* the device is provided beneath the rail foot *b* with a hole to receive a screw bolt *l*, one end of which forms a hook *m*, which embraces the opposite side of the rail foot, while the other end is provided with nuts *n*, which bear against the plate *o*.

The device is placed on the rail foot *b* in such manner that its bearing plate *h* bears against the side of the sleeper, whereupon the nuts *n* are tightened up. The hook shaped screw bolt *l*, *m*, with the aid of the nuts *n*, then presses the clamp firmly against the rail, whereby the latter is so connected to the clamp as to prevent creeping of the rail, owing to the resistance offered by the bearing surface *h* bearing against the sleeper *d*. The clamp thus formed provides a perfectly reliable anchorage for the rail, preventing the same from creeping. The clamping device can of course also be used with sleepers not provided with beveled edges *d¹*, in which case the face *i* of the neck *g* would not project beyond the bearing plate *h* but would touch the side of the sleeper. The clamping device can also be employed with iron sleepers instead of

wooden sleepers, and is in fact applicable to any system of laying rails on sleepers.

In Figs. 3 and 4 showing the device applied to a rail carried by chairs, *a* designates 5 a so-called bull head rail having a narrow foot *b* and a slightly bigger head *b*¹. This rail is secured in the known manner by a chair *c* on the sleeper *d* with the aid of a key *f*.

10 The clamping device itself is constructed in exactly the same manner as the device shown in Figs. 1 and 2 and consists of one part *g*, *h*, *i*, *o* and the clamping bolt *l*, *m*, *n*. The bearing plate *h*, which bears with a sufficiently large surface against the side of the sleeper *d*, is about the same width as the narrow foot *b*. The hook *m*, however, is in this case so shaped that it only engages slightly over the top surface of the rail foot, 15 and its upper surface *p* only projects slightly above the rail foot. The hook *m*, *p* consequently does not hinder the insertion or withdrawal of the key *f*.

What I claim as my invention is:

20 1. A rail clamp, comprising an elongated channel shaped neck adapted to partly embrace and engage one side of the foot of a

rail, a bearing plate depending from said neck at right angles to its longitudinal axis and adapted to bear against a sleeper, a web 35 connecting said neck and said bearing plate together, and a clamping bolt passing through said neck and forming a hook engaging the foot of the rail on the opposite side to that engaged by said neck. 35

2. A rail clamp, comprising an elongated channel shaped neck adapted to partly embrace and engage one side of the foot of a rail, a bearing plate depending from said neck at right angles to its longitudinal axis 40 and adapted to bear against a sleeper, a web connecting said neck and said bearing plate together, and a clamping bolt passing through said neck and forming a hook engaging the foot of the rail on the opposite 45 side to that engaged by said neck, said bearing plate having an inwardly depressed recess for strengthening the clamp.

In testimony whereof I hereunto affix my signature in the presence of two witnesses. 50

ADAM RAMBACHER.
